UNITED STATES PATENT OFFICE.

CLIFFORD ELBRIDGE COLE, OF BIRMINGHAM, ALABAMA, ASSIGNOR OF ONE-HALF TO SARAH A. WHITE, OF BIRMINGHAM, ALABAMA.

TELEPHONE INSTRUMENT.

No. 883,088.

Specification of Letters Patent. Patented March 24, 1908.

Application filed January 10, 1906. Serial No. 295,441.

To all whom it may concern:

Be it known that I, CLIFFORD ELBRIDGE COLE, a citizen of the United States, residing at Birmingham, in the county of Jefferson and State of Alabama, have invented new and useful improvements in Telephone Instruments, of which the following is a specification.

This invention relates to telephone instruments, and has for one of its objects to provide a receiver in which the entire volume of sound will be conveyed to the ear of the person receiving the message, one wherein the volume of sound may be readily controlled, thus obviating the indistinctness resultant upon loud talking into the transmitter, and one wherein the controlling or cut-off valve may be conveniently manipulated.

A further object of the invention is to provide a transnutting instrument into which the full volume of the voice of the sender will be concentrated, thus permitting the adoption of a low tone of voice in using the instrument, and at the same time obviating the confusion of other sounds within the transmitter, and one wherein the transmitter may be closed at will without cutting off communication with the other end of the line.

With these and other objects in view, the invention comprises the novel features of construction and combination of parts more fully hereinafter described.

In the accompanying drawings:—Figure 1 is a side elevation partly in section of a receiving instrument embodying the invention. Fig. 2 is a section taken on the line 2—2 of Fig. 1. Fig. 3 is a view similar to Fig. 1, showing a modified embodiment of the invention. Fig. 4 is a section taken on the line 4—4 of Fig. 3. Fig. 5 is an elevation partly in section of a transmitting instrument embodying the invention. Fig. 6 is a top plan view of the same. Fig. 7 is a front end elevation of the instrument.

Referring to the drawings, 1 designates a telephone receiver provided as usual with a head 2 having a conical or bell mouth 3 and a flexible transmitting diaphragm 4, these parts, except as hereinafter explained, being of the usual construction and material and adapted to perform their ordinary functions.

Formed in the head 2, the mouth 3 of which is of sufficient size to wholly cover the ear of the operator, is a transversely extending guide opening or slot 5 situated in ad-

vance of the diaphragm 4 and designed to receive a cut-off valve or slide 6, the stem 7 of which projects outward through a bearing opening in the head and terminates at its outer end in a head or push button 8 between which and the adjacent wall of the receiver there is disposed a compressible spring 9 adapted for maintaining the slide in normal position with the receiver wholly open.

When the device is in use the mouth of the receiver entirely covers the ear of the operator, thus excluding outside noises and permitting the message to be clearly distinguished, whereby the telephone may be used in public places without the necessity of providing a cabinet therefor. Should the party using the transmitter at the other end of the line raise his voice beyond the proper pitch the slide 6 may be adjusted for regulating the volume of sound produced in the receiver, thereby obviating the indistinctness usually attendant upon unduly loud talking into the transmitter.

In Figs. 3 and 4 the device disclosed is identical in construction and operation with that above described except that the valve 6' is pivoted at 10 to swing across the opening in advance of the diaphragm 4 and has its stem 7 provided with a curved segmental arm 11 terminating at its outer end in a head 12, there being disposed upon said arm a normally expanded spring 13 arranged to bear at one end against the head and at its other end against a projection or abutment 14 on the head of the receiver and serving to maintain the valve normally in open condition.

In Figs. 5 to 7 there is illustrated a transmitting instrument 15 having an enlarged conical or bell mouth 16 designed to wholly cover the mouth of the operator and provided with a flexible diaphragm 17, this instrument being, with the exception of the size of the mouth 16, of usual construction and adapted to perform its ordinary functions. Formed at the inner end of the head 16 is a guide opening or slot 18 disposed in advance of the diaphragm 17 and adapted to receive a cut-off valve or slide 19, the stem 20 of which carries a normally expanded spring 21 arranged to bear at its inner end against the adjacent wall of the head and at its outer end against a push button or head 22 provided on the stem.

In the use of the instrument the bell 16 wholly covers the mouth of the operator, whereby the instrument will be closed against the effects of external noises, thus 5 permitting the adoption of a low tone of voice in sending the message and preventing the latter being heard by parties standing near the instrument. When it is desired to conduct a conversation with some one near 10 the transmitter and without cutting off communication with the other end of the line, the slide 19 may be moved to closed position to prevent such conversation being heard by the party to whom the message is being sent. 15 From the foregoing it is apparent that I produce a simple device admirably adapted for the attainment of the ends in view, it being understood that in attaining these ends minor changes in the details herein set 20 forth may be resorted to without departing from the spirit of the invention.

Having thus described my invention, what I claim is:

A telephone instrument comprising a head having a bell-shaped mouth and a transverse slot or aperture intersecting the mouth, in combination with an imperforate slide engaging the slot or aperture and capable of being moved bodily into the path of the mouth of the instrument, said slide being provided with a stem projecting exteriorly of the body of the instrument and having a push button or head, and a spring coiled on the stem adjacent to the push button and engaging the latter to move the slide in one direction. 35

In testimony whereof, I affix my signature in presence of two witnesses.

CLIFFORD ELBRIDGE COLE.
